CLAIM

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee. 37 CFR 1.84 (a) (2)

FIG. 1 is a front view of a display screen or portion thereof with icon; showing the first embodiment of our new design; and,

FIG. 2 is a front view of a display screen or portion thereof with icon; showing the second embodiment of our new design.

The broken lines show a display screen or portion thereof, and form no part of the claimed design.
